(57) **CLAIM**

The ornamental design for a vehicle grille, as shown and described.

DESCRIPTION

FIG. 1 is a front left top perspective view of a vehicle grille according to the present invention.

FIG. 2 is a front left perspective view of the vehicle grille shown in FIG. 1.

FIG. 3 is a rear right top perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is another front view of the vehicle grille shown in FIGS. 1-10, but with the grille mounted on a vehicle, and with the rest of the vehicle shown in broken lines and unclaimed.

In FIGS. 1, 2, 4, 5, 6, 8, and 9, the broken lines define an unclaimed boundary that represents the location of a vehicle badge.

The broken line showing in FIG. 11 represents environmental subject matter that forms no part of the claim.
